1

This invention relates to electronic tuning devices used in wireless receivers having automatic volume control. In such apparatus it is frequently difficult to effect tuning by ear and for this reason use is frequently made of visual tuning. For this purpose an electron-ray indicator may be used, which comprises a discharge tube having a cathode and an anode, and one or more deflection electrodes which are subject to a voltage derived from the detector portion of the apparatus and which impart to the electron beam emitted by the cathode a deflection varying with this voltage. The anode is in most cases conical in shape and is internally coated with fluorescent material, the arrangement being such that the anode may be observed from the upper side of the tube. The tube is arranged in the apparatus in such manner that only the upper side is visible from the outside, the tube being preferably arranged behind an aperture provided in the cabinet of the apparatus. Consequently, when the apparatus is in operation, that side of the anode which can be observed from the outside has produced on it fluorescent spots the dimensions of which are a measure of the accuracy of tuning of the apparatus.

In most cases it is desirable to amplify the control voltage before being supplied to the deflection electrodes of an electron-ray indicator. The latter is therefore usually assembled with an amplifying system in a single envelope. This amplifying system may comprise a control grid, an anode connected to the deflection electrodes and a cathode, and the latter may be integral with the cathode of the indicator proper. The control grid has supplied to it a control voltage, whilst the anode is connected by way of a coupling resistance to the positive terminal of the high tension supply. The amplification furthermore affords the advantage that the deflection voltage has the polarity which is generally desired.

It has been found, however, that when use is made of such indicators, the optimum variation of the deflection with signal strength is not always obtained, since in many cases it is desirable that the indicator should not respond to comparatively weak signal voltages and should become operative only when the signal voltage exceeds a certain limit.

In order to obviate this disadvantage, the electron beam is, according to the invention, not only responsive to the action of the amplified control voltage but also to the action of a voltage derived directly from the anode or screen-grid circuit of a tube situated in the signal channel, the

2

amplification of which is controlled as a function of the signal voltage.

The invention is based on the fact that the width of the fluorescent spot is controlled by this second voltage only at higher signal strength. The anode of the said amplifying tube is preferably connected through a coupling resistance to the screen grid of a tube controlled in amplification, this screen grid being connected by way of a supply resistance to the positive terminal of the high tension supply. In this case the screen grid of the tube controlled in amplification will have a voltage which increases with increasing signal strength, since the screen grid current decreases with increasing signal strength.

The invention is of particular importance for circuit-arrangements in which an electron-ray indicator having two sensitivities is provided. These two sensitivities are usually obtained by utilising two amplifying systems, the control grids of which are interconnected, but of which one control grid, for example due to its being wound with a different pitch, imparts to the associated amplifying tube an amplification factor which is different from that of the other amplifier. The indicator portion comprises two deflection systems, of which one is subject to the action of the voltage at the anode of one amplifier and the other to the action of the voltage at the anode of the other amplifier. As a rule, two luminous spots are then visible on the fluorescent screen of the indicator whilst the deflection systems act upon the width of the shade sectors between these spots. Since the two amplifiers have different amplification factors, the angular variation of one sector upon variation in signal strength and tuning is much quicker than that of the other, i. e. the sensitivity of one sector is much greater than that of the other sector. One sector may serve for tuning to stations the signal strength of which is comparatively small and the other sector for tuning to stations having a greater signal strength.

The disadvantage of such a device is that, when the grids of the amplifiers are connected to a resistance included in the detector portion of the receiver, the less sensitive portion operates upon reception of comparatively weak signals and may already exhibit a comparatively great deflection. It is thus frequently impossible to tune to local transmitters by the visual indicator. By applying the invention to the indicator portion having the smaller sensitivity, this portion will not respond to the reception of stations the signal strength of which lies below a certain limit, so

that the opening angle of the shade sector of the insensitive portion does not increase until the signal strength of the received station has a comparatively high value.

In order that the invention may be readily carried into effect, one example of the invention applied to such a device will now be described in detail by reference to the accompanying drawing which is a schematic circuit diagram showing that part of the arrangement which is essential to the invention.

In the figure, reference numeral 1 designates the input terminals of an input band-pass filter comprising two circuits 2 and 3 and to which the incoming intermediate frequency oscillations are supplied. Tube 4 is an intermediate frequency amplifying tube having a cathode 5 and a control grid 6 which has supplied to it the intermediate-frequency oscillations. The tube furthermore comprises a screen grid 7, which is connected by way of a resistance 33 to the positive terminal of a source of supply, and a suppressor grid 8, connected to the cathode. The first circuit 9 of a second intermediate frequency filter 9, 10 is connected to the anode. A tapping on the coil of the second circuit 10 is connected to the anode of a detector tube 11, the cathode of which is grounded. The detector circuit furthermore comprises two series-connected resistances 12, 13, the second of which has derived from it the low-frequency modulation voltage which is supplied to terminals 14. The condenser 15 operates as a short-circuit for the intermediate-frequency currents.

Furthermore, provision is made of automatic volume control. A voltage of intermediate frequency is derived by way of a condenser 17 from the circuit 9 and supplied to a diode anode 15 incorporated in the tube 4. This diode circuit furthermore comprises a resistance 18, across which occurs not only the modulation frequency but also direct voltage which is proportional to the amplitude of the carrier wave and which serves as a control voltage for the automatic volume control. This voltage is supplied by way of a filter comprising a resistance 19 and a condenser 20 to the grids of the preceding high-frequency and intermediate-frequency amplifying tubes. The amplification of the intermediate-frequency amplifying tube 4 is controlled by the direct voltage which is taken from the resistance 13 and which is likewise proportional with the amplitude of the carrier-wave. This direct voltage is supplied to the lower end of circuit 3 by way of a filter comprising a resistance 21 and a condenser 22.

For the indication of tuning, provision is made of a tube 23 having a cathode common to a plurality of electrode systems and connected to earth. The tube comprises two triode amplifiers, the grids 25 of which are interconnected, whilst an anode 26 is connected by way of a coupling resistance 31 to the positive terminal of the source of supply voltage. The grid associated with this anode is wound with a pitch smaller than that of the grid associated with a second anode 27 so that the gain factor of the first triode is greater than that of the second triode. Tube 23 furthermore comprises an indicator system having an anode 30 and two deflection electrodes 28 and 29 which, as a rule, have the form of rods. The anode is covered in known manner with fluorescent material and the deflection electrodes are so positioned that two luminous spots separated by shade sectors are seen on the cathode. The de-

flection electrodes 28 and 29 are connected to the anodes 26 and 27. The voltage set up across resistance 13 is active at the grid 25.

The operation of the arrangement described is such that if the voltage across resistance 13 increases, for example due to an increase in signal strength as a result of the correct point of tuning being approached, the electron current flowing to the anode 26 decreases so that the voltage at the anode itself increases as a result of the voltage loss across the resistance 31 and one shade sector on the fluorescent screen of the anode decreases in width. With correct tuning the width of the shade sector is as small as possible. The voltage across resistance 13 is also active at the grid of the second triode the sensitivity of which, however, is much smaller so that the voltage at the second deflection plate 28, upon variation in the voltage across resistance 13, is varied to a much smaller extent and the associated shade sector shows a much smaller decrease in width.

It has been common practice to connect the anode 27, similarly as the anode 26, by way of a coupling resistance to a point of constant potential. However, in this case undesired variation in the width of the shade sector still occurs upon reception of weak stations. According to the invention, this disadvantage is obviated by connecting the anode 27 by way of a coupling resistance 32 to the screen grid 7 of the tube 4, controlled in amplification. It is thus achieved that the voltage at the anode 27 for a small signal strength has so small a value that variation in the shade sector corresponding to the deflection plate 28 substantially does not occur up to a predetermined limit of the signal strength. It is only upon reception of strong signals that the control voltage at the control grid 6 of the tube 4 has so high an absolute value that a high voltage is set up at the screen grid so that a controlling action is exerted upon the shade sector associated with deflection plate 28. Furthermore, the triode 24, 25, 27 may also exert a controlling action in the normal way, although this is not always required for satisfactory operation of the device.

It has been found that satisfactory operation of the circuit-arrangement may be ensured at a value of 250 volts for the supply voltage and with the use of resistances 31 and 32 having values of 1 and 2.2 megohms respectively. At the normal value of the resistance 33 included in the screen-grid lead, there will be an increase in the voltage at the screen grid from 85 to substantially 250 volts if the signal voltage varies from a given minimum value into a high maximum value. Consequently, in the circuit-arrangement according to the invention, the width of the shade sector for the indication at great signal strength is controlled not only by the variation in the anode current of the amplifying triode, which is due to variation in the voltage at the control grid, but also by the variation in the voltage at the anode as a result of the variation in supply voltage, the last-mentioned control as a rule being the main control. It has been found that it is readily possible to provide an adjustment at which the insensitive portion of the indicator circuit does not become operative until the extreme working limit of the sensitive portion is attained.

The operation may even be slightly improved by including a resistance 35 between the anode of the insensitive triode and earth. This resistance may have a value of about 2 megohms.

The circuit-arrangement according to the invention thus affords the advantage of a material

improvement in operation without additional elements being required.

What I claim is:

1. In a radio receiver provided with an intermediate frequency amplifier including an electron discharge tube having a screen grid electrode and an electrode, a detector coupled to the output of the intermediate frequency amplifier and means to automatically control the volume of said intermediate frequency amplifier in accordance with the detected signal, a tuning indicator for said receiver comprising an electron ray tube having an amplifier section and a cathode-ray indicating section provided with a deflection system and a fluorescent target, means to supply the detected signal to the amplifying section of said electron ray tube, means to derive a control signal from one of the electrodes of the tube in the intermediate frequency amplifier, and means to supply said control signal to said electron ray tube whereby the resultant visual indication of said target is dependent both on said detected signal and said control signal.

2. A radio receiver as set forth in claim 1 wherein the control signal is derived from the screen grid electrode of the tube in the intermediate frequency amplifier.

3. In a radio receiver provided with an intermediate frequency amplifier including an electron discharge tube having a screen grid electrode and an anode electrode, a detector coupled to the output of the intermediate frequency amplifier and means to automatically control the volume of said intermediate frequency amplifier in accordance with the detected signal, a tuning indicator for said receiver comprising an electron ray tube having an amplifier section and a cathode-ray indicating section provided with two deflection elements, an electron beam source and a fluorescent target, means to supply the detected signal through the amplifying section of said electron ray tube to one of said deflection elements to effect beam deflection with respect to said target for detected signals of low signal strength, means to derive a control signal from one of the electrodes of the tube in the intermediate frequency amplifier, and means to supply said control signal to the other of said de-

10
15

flection elements to effect beam deflection with respect to said target for detected signals of increased signal strength whereby the resultant visual indication of said target is dependent both on said detected signal and said control signal.
